UNITED STATES PATENT OFFICE.

JOHN C. POORE, OF BOSTON, MASSACHUSETTS.

DOLL.

1,334,470.

Specification of Letters Patent. Patented Mar. 23, 1920.

Application filed April 5, 1919. Serial No. 287,669.

To all whom it may concern:

Be it known that I, JOHN C. POORE, a citizen of the United States, residing at Boston, in the county of Suffolk, in the 5 State of Massachusetts, have invented a certain new and useful Improvement in Dolls, of which the following is a specification, reference being had to the accompanying drawings.

10 The object of this invention is to provide a simple and reasonably cheap doll embodying, in the head portion thereof, mechanism by means of which the eyes of the doll may be moved at will into every natural position; 15 the eye controlling mechanism being, preferably, so arranged that the life-like appearance of the head is in no way or degree changed.

Briefly described my invention consists of 20 mechanism concealed in the head and connected with the ears of the doll; in such manner that, by properly manipulating the ears, the eyes may be caused to turn to the right or left or may be moved vertically.

25 For the purpose of explaining my said invention clearly I have provided the annexed drawings, in which the Figure 1 is a front view of a doll's head having my present improved mechanism mounted therein; the 30 supporting frame of said mechanism being indicated by dotted outline.

Fig. 2 is a detached, side view of one of the eye-supporting levers. Fig. 3 is a top view of the eye-operating mechanism, removed from the doll's head and Fig. 4 is an end elevation of the same.

Fig. 5 is a relatively enlarged detail, plan, view of one of the eye-operating levers and its supporting and actuating means.

40 In these drawings the doll's head is indicated by the letter *a* and the ears by the letters *b* and *c*, said ears being fixedly secured to the ends of eye-operating rods, as I will explain more explicitly hereinafter.

45 Within the head *a* is a frame formed, as here shown, with opposing, parallel, side walls *d*—*d'* which are connected by end portions *e*—*e'* in which ends are slidably and rotatably mounted rods *f*—*f'* to which the 50 ears of the doll are secured. The rods *f* and *f'*, are loosely supported, about midway of their length, by brackets *g*—*g'* which are

secured to one of the side walls of the supporting frame.

The eye-balls are denoted by the letters *h*—*h'* and they are mounted, respectively, on one end of levers *i*—*i'* that are formed with balls *k*—*k'*, about midway the length of the said levers, and the balls *k*—*k'* are fulcrumed in frictionally acting spring sockets *m*—*m'* in such manner that the eye may be rocked vertically and laterally within certain prescribed limits, in order to permit all usual, or natural, movements to the eye balls. The inner end portions of the levers *i* and *i'* are provided with heads *n*—*n'* which have openings adapted to receive, respectively, eccentrics *o* and *o'* that are mounted fixedly on the inner ends of the rods *f* and *f'*; the arrangements of the parts thus far described being such that, when the ears are grasped and drawn outward or pushed inward, the connected eyes will be moved laterally and, when the said rods are rocked in their bearings, the eyes will be moved vertically. Each eye may be controlled independently, as to its movements, or may be caused to move in unison, by properly manipulating the ears of the doll.

Referring now to Fig. 3 of the drawings, 80 it will be seen that the rods *f*—*f'* are provided with spiral springs *p*—*p'* which extend both sides of the brackets *g*—*g'*, one end of each spring abutting the end wall of the frame and the other end abutting a 85 collar *s* or *s'*, as the case may be, which is fixed on the rod *f* or *f'*. The collar *s'* abuts the eccentric *o'* and a like collar *s* abuts the said eccentric at its other side, as is perhaps best seen in Fig. 5 of the drawings, the arrangement of parts being such that, when the rods *f*—*f'* are moved longitudinally, in either direction, the springs will return the rods to their respective normal position.

90 The manner of securing the described eye-operating mechanism in the head of the doll is not material.

It may be accomplished by removing the top of the said head and inserting the mechanism or it may be done by molding 100 the head around the mechanism.

Having thus described my invention, I claim:

1. In combination in and with a doll's

head, movable eyes and means connected with the doll's ears for manually moving said eyes.

2. In combination in and with a doll's head, movable eyes, and means connected with the doll's ears for independently moving said eyes.

3. In combination in and with a doll's head, movable eyes, means connected with 10 the doll's ears for moving said eyes, and

means consisting of springs for automatically returning the eyes to their initial positions.

4. In combination in and with a doll's head, independently movable eyes mounted 15 in said head, means for manually moving said eyes, and means consisting of spiral springs for returning the eyes to their initial positions.

JOHN C. POORE.
